(57) **CLAIM**

The ornamental design for an evacuable, resealable bag, as shown and described.

DESCRIPTION

FIG. 1 is a perspective view of the evacuable, resealable bag, showing an embodiment of the present design;

FIG. 2 is a front elevation view of the embodiment of the present design illustrated in FIG. 1;

FIG. 3 is a rear elevation view of the embodiment of the present design illustrated in FIG. 1;

FIG. 4 is a right elevation view of the embodiment of the present design illustrated in FIG. 1;

FIG. 5 is a left elevation view of the embodiment of the present design illustrated in FIG. 1;

FIG. 6 is a top plan view of the embodiment of the present design illustrated in FIG. 1;

FIG. 7 is a bottom plan view of the embodiment of the present design illustrated in FIG. 1.

FIG. 8 is an exploded perspective view of the present design illustrated in FIG. 1;

FIG. 9 is a front elevation view of a second embodiment of the present design without a writing surface;

FIG. 10 is a rear elevation view of a third embodiment of the present design wherein the writing surface is on the rear of the bag; and,

FIG. 11 is a front elevation view of a fourth embodiment of the present design illustrating an alternative valve location.
